UNITED STATES PATENT OFFICE

KENT A. HAWLEY, OF VICTOR, NEW YORK, ASSIGNOR TO LOCKE INSULATOR CORPORATION, OF BALTIMORE, MARYLAND, A CORPORATION OF MARYLAND

INSULATOR

Application filed July 15, 1924. Serial No. 726,153.

My invention relates to insulators of the type embodying a member of insulating or dielectric material connected to a metallic part through the intervention of a resilient medium. At the present time the connecting medium generally employed is Portland cement.

The primary object of the invention is to afford simple, practical and efficient means for effecting the orderly distribution and control of the internal mechanical forces to which insulators of the character indicated are subjected.

The dielectric material most commonly used in insulators is porcelain which, as is well known, is capable of sustaining very heavy compressive loads but is of comparatively low strength when acted on by shearing stresses or when subjected to tension.

These characteristics of porcelain have rendered it apparent that the mechanical forces applied to this dielectric material in an insulator should, so far as possible, be compressive, and that shearing and tensile forces should be avoided or maintained within safe

limits. If porcelain or other dielectric material having similar strength characteristics is subjected to a compressive force applied to a small area, the elasticity of the material permits a compression of the area subjected to the force, thus causing shearing forces to be developed between such area and the surrounding portions of the porcelain body, and thereby frequently resulting in the

failure of the insulator by shearing rather than by direct compression. Not only has it been realized that concentrated loads applied to the dielectric material often produce the effect described but it is also appreciated

that such loads are a cause of incipient cracks in the dielectric material leading to electrical break down of the insulator. Attempts have heretofore been made to apply the mechanical forces to the porcelain or dielectric body of an insulator so as to load the dielectric ma-

terial in a manner avoiding excessive concentrations of force thereon, thus producing an insulator of high mechanical strength. These attempts have in general sought to distribute the load to the insulating member and to relieve the latter of undue stress in any particular part either by radially slitting or otherwise forming the metallic bolt or cap of an insulator so that such metallic part would be capable of yielding, stretching or flexing, or by providing upon the metal members associated with the insulating member, or upon the insulating member itself, resilient or relatively flexible projections embedded in the cement interposed between and employed to connect the metal parts of the insulator with the insulating member of porcelain or other dielectric material. These projections, which at one end are integrally attached or rigidly anchored to the insulator part by which they are carried, act after the fashion of flexible or resilient cantilevers which deflect under stress and thus, by their yielding, effect a reduction in the stress which otherwise might have a higher degree of concentration at a given point. Where the resilient projections have been in the form of flexible flanges it has been proposed to control their relative flexibility either by varying their angularity or their thickness so as to modify stiffness and effect a corresponding distribution of the load to the member of dielectric material, and it has also been proposed to effect such distribution by varying the spacing between the projections.

Means of this character not only have the disadvantage of increasing the cost of insulators but it is obvious that the control of the mechanical stresses in the insulator can thereby be obtained only in a general way and with considerable uncertainty, because the forces transmitted from the projections to the porcelain or dielectric member of the insulator are affected and subject to modifi-

cation in being transmitted through the intervening cement.

By my invention the desired distribution of forces upon the dielectric body is accomplished by proportionally varying the thickness of the elastic cement interposed between said dielectric body and the metallic members associated therewith, and by forming the surfaces of the metallic members which bear upon the cement so as to result in the desired distribution of force to the latter. It will be perceived that by suiting the thickness of cement to the form of the metallic surface bearing thereon the stresses communicated to the porcelain body member may be controlled with substantial definiteness and certainty.

Before proceeding with a description of the particular applications of the invention illustrated in the drawings, the general characteristics thereof will be explained in order that the production of modified forms of insulators involving such other distributions of stresses as may be desired to suit special conditions can be readily effected. The load delivered to the cement at any point depends upon the ability of the cement to receive it, that is to say, it is dependent upon the rigidity of the cement, or in other words is inversely proportional to the amount the cement yields. As the ability of the cement to yield is proportional to its thickness, the load delivered is therefore inversely proportional to the thickness of the cement for uniform compressive movements of the latter. It therefore will be perceived that compression load imparted to the cement will be uniformly distributed if the compressive movement is proportional to the cement thickness and that desired variations in the distribution of the compressive load may be effected by correspondingly varying the cement thickness or the extent of its compressive movement. The cement thickness may be readily varied by suitably spacing the metallic parts of the insulator from the porcelain body member in a direction normal to the bearing or working surface of the metallic part at any given point; while the compressive movement of the cement may be controlled by varying the slope of the working surface of the metallic member which bears upon the cement. It will be perceived that by varying the relation or value of these two factors to each other the forces applied to the dielectric body may be controlled and distributed in any desired manner, whether to produce uniform loadings or graduated loadings, progressively increasing from unstressed parts of the porcelain.

When the porcelain body member of an insulator is subjected to stress by external forces applied to a metallic member of the insulator having an angularly disposed working face bearing upon the cement in the space between said members a slight movement of

the metallic member occurs in the direction of its axis, which is the direction of application of the external load. This movement produces a compression of the cement in a direction normal to the working surface of the angularly disposed face, the amount of said compression being equal to the amount of said movement multiplied by the sine of the angle subtended between the axis of the metallic part and the bearing surface of the angular face at the point in question. Since, as has been pointed out, the load which the cement is capable of receiving and transmitting to the porcelain is inversely proportional to the thickness of the cement, it will be appreciated that the value of this load or stress may be caused to vary in proportion to variations in the ratio defined by the compression of the cement divided by its thickness; and as the extent of compression of the cement for an axial movement of the metallic part of the insulator thereto of a given external force varies with the sine of the angle which the working face of the metallic part forms with the axis of said part, it will be perceived that the load transmitted by the cement to the porcelain may be varied as desired by modifying either the thickness of the cement at different points while maintaining constant the angularity of the working faces of the metallic part bearing against the cement, or by varying the angularity of said working faces while maintaining a constant thickness of the cement, or by varying both the angularity of the faces and the corresponding thicknesses of the cement to cause these factors to be related to each other in the desired ratio. The relation between the load on the cement, its thickness and the angularity of the working surface at any given point of the metallic member of the insulator may be expressed in the form of an equation, thus:

$$L = \frac{a \sin \alpha \cdot M}{t} \quad 110$$

where L equals load on cement; a is the movement of the metallic insulator member in the direction of its axis; α is the angle subtended between the axis of the metallic member and the surface of the metallic member bearing upon the cement at the point in question; M is the modulus of elasticity of the cement, and t is the thickness of the cement between the metal member and the porcelain measured normal to the working surface of the former at the point in question. If, therefore, it is desired to impress equal loadings on the porcelain or dielectric body at any given points such result may be effected by maintaining constant the respective ratios or relations between the angle of the bearing face at the individual points and the corresponding thicknesses of the cement at those points, for it is to be observed that the preservation of

the equality of these ratios results in equal loadings of the cement, since the modulus of elasticity of the cement and the extent of axial movement of the metal member of the 5 insulator under the application of a given external load are constant factors. On the other hand, if it is desired to impress different loadings on the porcelain at different points, as at times may be advantageous, such 10 result may be effected by causing the said ratios at the respective points to bear the relations it is desired that the stresses on the porcelain shall have to each other.

In the foregoing formula no factor is introduced 15 allowing for the elasticity of the insulating and metallic members, which are relatively inelastic as compared with the cementing material interposed between them. If, however, it is desired in any special case 20 to carry the accuracy of the distribution of load on the insulating member to a point of refinement where the elasticity of the insulating and metallic members cannot be regarded as negligible, then a corresponding modifying 25 factor may be introduced into the formula.

In the drawings illustrating embodiments 30 of the invention in preferred forms of insulators,—

Figure 1 is a view partly in elevation and partly in section of an insulator of the suspension type in which the mechanical stresses imparted to the porcelain are distributed with substantial uniformity.

Figure 2 is a view partly in elevation and partly in section of a slightly different form 35 of suspension insulator in which the loading of the porcelain or dielectric body is substantially uniform.

Figure 3 is an enlarged detail view of a portion of one of the metallic eye bolts of the insulators illustrated in Figs. 1 and 2.

Figure 4 is a view, partly in elevation and partly in vertical section, of a strain insulator 45 especially suitable for connection to guy wires for radio towers or for use under similar conditions where the voltage is high, the amperage low, and the mechanical stresses are great.

Figure 5 is a diagrammatic view of an insulator unit suitable for the insulation of 50 radio towers.

The insulator illustrated in Fig. 1 is of the suspension type involving a metal cap 1, 55 a dielectric body member 2 and a metallic eye bolt 3. The insulating body member 2 is commonly formed of porcelain and the metal members 1 and 3 are connected thereto through the intervention of Portland cement 60 or other elastic cementing material interposed between the said metal members and the dielectric body member 2, as indicated at 4 and 5. To enable the bodies of cement 4 and 5 to be firmly bonded to the porcelain insulating 65 body member 2, the inner and outer faces

of the latter may advantageously be sanded, as at 6 and 7; and to provide an elastic joint or cushioning means to compensate for temperature changes the upper outer portion of the body member 2 and the upper end of the 70 eye bolt 3 may be advantageously coated, as at 8 and 9, respectively, with cut sarco.

The metallic cap 1 and the bolt 3 are each provided with working faces for transmitting 75 force to the cement which are inclined to the axis of the insulator, each of said metal parts preferably having a plurality of the working faces arranged in the form of steps.

The working faces 10 of the cap 1 are annular and formed on the interior of the cap, while 80 the working faces 11 of the eye bolt 3 are, of course, on the exterior of the latter near the upper end thereof. To facilitate slippage of

the bearing faces 10 of the cap with respect to the cement 4 with which said faces cooperate, it is preferred to coat the stepped working faces of the metal cap with sarco or other material suitable for the purpose, as indicated at 12. For a similar reason it is preferred 85 to coat the stepped working faces 11 of the eye bolt 3 with a sarco dip, as indicated at 13. As will be appreciated, the load which an insulator is required to support when in service causes a movement of the bolt along its axis and a movement of the cap 1 along 90 its axis, these movements of the metal parts being due to the stretching and yielding of the insulator elements under the imposed load and inducing corresponding slight movements of the cap 1 and bolt 3 with respect to the adjacent bodies of cement and porcelain body member 2.

The working faces 10 and 11 of the cap 1 and bolt 3, respectively, are convexly curved, 95 the curvature of the said surfaces being such that the distance to the adjacent surface of the porcelain body member 2 measured normal to the curved surface of the metal member at any point is proportional or approxi-

mately so to the sine of the angle subtended 100 between the axial line of the metal member and the surface of its working face at the point in question. This most advantageous character of the curved working faces or

bearing surfaces of the metal cap and bolt 110 will be readily understood from a consideration of Fig. 3, which is a diagrammatic view illustrative of one of the bolt members. In

this diagram the line $x-x$ indicates the center line of the bolt; the line $z-z$ is tangent to 115 the upper curved working face 11 at the point f ; and the line $y-y$ which extends at right angles to the tangent $z-z$ therefore is normal to the direction of curvature of the step 11 at the point f .

The angle α subtended between the lines $x-x$ and $z-z$ will vary, it 120 will be noted, as the point f shifts along the curved working face 11 of the bolt, becoming greater as the point upon the curved surface approaches the next lower step and growing 125 130

less as it approaches the upper end of the bolt. The sine of the angle therefore will correspondingly vary and the distance to the adjacent face of the porcelain body member 5 should therefore be increased or diminished as the case may be to vary the thickness of cement corresponding substantially thereto. In the case of the metal cap 1 the angle α subtended between its axis and the line which is 10 tangent to a curved bearing face at any given point is preferably less than the corresponding angle α of the working face 11 of the eye bolt 3 opposed thereto. This results in enabling the working faces of the cap 1 15 to deliver inwardly directed radial pressure to the porcelain body member 2 in excess of the radial outward pressure communicated to the porcelain member from the bolt 3, thus ensuring that the porcelain shall be in compression instead of being subjected to tension forces, which latter condition would result if the outwardly directed pressure induced by the bolt exceeded the inwardly directed pressure from the cap and thus applied to the 20 porcelain member 2 a bursting force tending to increase its diameter.

It has already been pointed out that the weights or loads which insulators are required to sustain in service cause an elongation of 30 the metal cap 1 in the direction of its axis and also produce a corresponding movement of the bolt 3 with respect to its axis. Where the portion of the cap 1 on which the working faces 10 are formed is of a thickness such that the stretching or yielding of the cap is 35 substantially equal for corresponding units of length, the movement of the uppermost working face 10 in the direction of length of the axis of the cap will, it will be appreciated, be greater than the movement of the lower inclined faces 10, the extent of movement progressively decreasing and that of the lowermost face 10 being least. The load supported by the insulator similarly induces 40 movements of varying amount of the working faces 11 of the bolt 3 in the direction of length of the axis of the latter, but in this case the lowermost working face 11 of the bolt moves to the greatest extent. As compared with the movement of the working faces of the cap, the movement of the working faces of the bolt is usually less in amount because of the far greater ability of the bolt 45 to resist stretching. When, as in some instances, it is advantageous, it is desired to eliminate or compensate for such variations in the loading of the porcelain body member 2 as may be induced by unequal movements of the inclined working faces 10 and 11 of the cap 1 and suspension bolt 3, respectively, this 50 may be accomplished by varying the thickness of the cement between the porcelain and the respective metal parts in correspondence to the differences in movement of the inclined working faces of the cap and bolt, the cement 55

being thicker opposite the working faces having the greater movement. As shown by the upwardly diverging dot and dash lines 14 and 14', the thickness of the body of cement 4 between the working faces of the cap 1 and 70 the adjacent surface of the porcelain body member 2 illustrated in Fig. 1 is gradually increased upwardly for this purpose, while, as indicated by the dot and dash lines 15 and 15' the thickness of the body of cement 5 between the working faces of the bolt 3 and the adjacent surface of the dielectric member 2 is increased downwardly.

A somewhat different form of suspension insulator involving the same principles of 80 construction is illustrated in Fig. 2, such insulator being intended for use where lighter loads are required to be sustained. In this insulator the metallic cap 17 is provided with only two curved inclined working faces 18, 85 and the curved working faces 19 of the suspension bolt 20 are fewer than those with which the suspension bolt 3 is provided. The metallic members of the insulator are connected to the porcelain body member 21 90 thereof through the intervention of interposed bodies of Portland or other resilient cement. The insulator shown in Fig. 2 preferably is otherwise similar to the construction heretofore described, and accordingly 95 corresponding reference numerals have been applied thereto to indicate the similar features of construction.

Fig. 4 shows an application of my invention to a compression type of insulator intended to operate under very heavy mechanical loads. This insulator comprises a pair of metallic housings 22 which are rigidly connected by means of bolts 23. For the purpose of forming a moisture excluding 100 joint a lead filling may be interposed between the housing members as indicated at 24. Encircled by the enveloping frames or housings 22 are oppositely disposed insulating members 25 of porcelain or other suitable 105 dielectric material, each of the said insulating members being provided with an inclined shoulder or working face 26 bearing against a body of insulating cement 27 interposed between the insulating member 25 and the metallic housing 22. The inner surface of each of the porcelain members 25 is also formed with an inclined working face 28 which is preferably parallel to the corresponding outer face 26. Between this inner face and a metallic nut 29 upon the end of one of the metal eye bolts 30 forming a part of the insulator unit is an interposed body of resilient cement 31. The slope of the peripheral surface of the nut 29 preferably corresponds to that of the bearing faces 26 and 28 of the insulating member 25. To hold the internal parts in proper relation during erecting and shipping, a porcelain spacer block 32 may be employed, springs 110

33 being interposed between the block and the respective nuts 29.

The particular design of insulator shown in Fig. 4 illustrates an application of the invention wherein the stresses imparted to the porcelain insulating bodies 25 are not uniformly distributed but are varied for the purpose of producing a somewhat gradual transmission of the stress from the area subjected to maximum pressure to the portion of the porcelain which is unstressed. To effect this purpose the bodies of cement 27 and 31 are gradually increased in thickness at their ends as indicated at 34. These thickened portions of the cement may be conveniently provided for by forming corresponding grooves in the housing members 22 and nuts 29, said grooves, as shown, preferably being lipped to prevent the cement from spalling at the ends. Since, as has already been pointed out, the load delivered to the cement at any point depends upon the ability of the cement to receive it, and as this ability depends upon the thickness of the cement which determines the extent to which it may yield, it will be perceived that by thickening the cement bodies at the points 34 the stresses imparted to the porcelain insulating members 25 at these points are enabled to be gradually reduced as desired. The bodies of cement 27 and 31 are preferably made comparatively thick so that irregularities of the metal housings 22 and porcelain body members 25 cannot cause concentration of excessive loads on the porcelain.

The insulator unit for radio towers illustrated in Fig. 5 diagrammatically discloses an elementary design for delivering compression load from one metal part to another through a porcelain body which is separated from said metal parts by intervening layers of resilient cement, the thickness of the cement being varied to distribute the load to the porcelain as desired. In the construction here shown two metal members 35 are disposed on opposite sides of a plate-like porcelain body 36 and between the latter and the metal parts are intervening bodies of Portland or other resilient cement 37. In the application of this insulator unit to radio towers the upper metal member 35 is designed to receive the load from the tower and the lower metal member rests upon any suitable foundation. The layers of cement 37 are increased in thickness at their ends as indicated at 38, thus causing the load communicated to the porcelain to be less adjacent the outer edges of the cement.

It will be perceived that my invention provides simple, efficient, cheap and reliable means for controlling the stresses induced in the dielectric member of an insulator by the load the insulator is required to sustain, and that a uniform distribution of stresses or a non-uniform distribution thereof of a

predetermined character may be readily attained.

I claim:—

1. An insulator comprising a dielectric member, a load receiving member in spaced relation to said dielectric member, and a body of material interposed between said members and serving to transmit stress from one to the other, the said load receiving member having a working surface whose distance from said dielectric member at a given point as measured in a direction normal to said working surface is approximately proportional to the sine of the angle subtended between the axis of said load receiving member and the direction of said working surface at said point. 75

2. An insulator comprising a dielectric member, a load receiving member in spaced relation to said dielectric member, and a body of cementitious material interposed between said members and serving to transmit stress from one to the other, said load receiving member having a plurality of working surfaces disposed in stepped relation and adapted to impart compressive force to said resilient material, said working surfaces being convexly curved and of spherical shape throughout so that tangents to said surfaces at different points subtend different angles with the axis of said load receiving member, and the thickness of said material at corresponding points varying respectively with the sine of said subtended angles. 95

3. An insulator comprising a dielectric member, a load receiving bolt in spaced relation to said dielectric member, and a body of cementitious material interposed between said bolt and said dielectric member and serving to transmit stress from one to the other, said bolt being provided with a plurality of working surfaces for imparting compressive force to said material, and each of said working surfaces being convexly curved and spherical throughout the area thereof by 110 which compressive force is communicated to said material. 105

4. An insulator comprising a dielectric member, a load receiving bolt in spaced relation to said dielectric member, a body of cementitious material interposed between said bolt and said dielectric member and serving to transmit stress to said dielectric member, a load receiving cap encircling said dielectric member in spaced relation thereto, and a body of cementitious material interposed between said cap and said dielectric member and serving to transmit compressive stress to the latter, said bolt and said cap each being provided with a plurality of inclined working surfaces for imparting compressive force to the said material adjacent thereto, the inclination of said working surfaces of the cap with respect to its axis being less than the inclination of said working sur- 130 115 120 125

faces of said bolt with respect to its axis, whereby tensional forces tending to be induced in said dielectric member by the outward radial thrust of said bolt are overcome.

- 5 5. In an insulator, a dielectric member having a cavity therein, a load receiving bolt located within said cavity, a mass of material embedding said bolt, the bolt having a plurality of steps each of spherical formation throughout its major portion and connected with the next adjacent step by a frusto-conical portion.
- 10

In testimony whereof I affix my signature.

KENT A. HAWLEY.
